UNITED STATES PATENT OFFICE.

ANDRÉ M. MERTZANOFF, OF BUFFALO, NEW YORK, ASSIGNOR TO AMERICAN RADIATOR COMPANY, OF CHICAGO, ILLINOIS, A CORPORATION OF NEW JERSEY.

COMBINED BOILER AND RADIATOR.

1,334,667.

Specification of Letters Patent. Patented Mar. 23, 1920.

Application filed November 27, 1916. Serial No. 133,689.

To all whom it may concern:

Be it known that I, ANDRÉ M. MERTZANOFF, a subject of the King of Greece, residing at Buffalo, Erie county, in the State of New York, have invented certain new and useful Improvements in Combined Boilers and Radiators, of which the following is a full, clear, and exact specification.

My invention relates to improvements in heating apparatus, and the same has for its object more particularly to provide a simple, efficient and reliable heating apparatus which requires no piping, and which may be readily installed without calling for skilled labor.

Further, said invention has for its object to provide a heating apparatus comprising a combined boiler and radiator which shall be neat in appearance, compact in form, and readily portable.

Further, said invention has for its object to provide a combined boiler and radiator which may be enlarged or extended proportionally as greater capacity is demanded.

Further, said invention has for its object to provide a combined boiler and radiator, in which the heat emitting or extended surface of its radiator portion is many times greater than, but in predetermined proportion to, the heat absorbing surface of its boiler portion.

Further, said invention has for its object to provide a combined boiler and radiator having means therein for receiving a burner and a supply of liquid fuel for operating said burner.

Further, said invention has for its object to provide a combined sectional boiler and radiator in which only certain of said sections have their surface exposed to the direct action of the heating agent and act as heat absorbing members, and the other of said sections, although connected to and communicating with said heat absorbing members, act only as the heat emitting or radiator members.

Other objects will in part be obvious and in part be hereinafter described.

To the attainment of the aforesaid objects and ends, my invention consists in the novel details of construction, and in the combination, connection and arrangement of parts

hereinafter more fully described and then pointed out in the claims.

In the accompanying drawings forming part of this specification, and wherein like numerals of reference indicate like parts—

Figure 1 is a front view showing one form of a combined boiler and radiator constructed according to and embodying my said invention;

Fig. 2 is an end view thereof;

Fig. 3 is a back view;

Fig. 4 is a section taken on the line 4—4 of Fig. 1 showing the fuel compartment. 65

Fig. 5 is a similar view on the line 5—5 of Fig. 1, showing the combustion chamber and the flue extending therefrom;

Fig. 6 is a detail rear view of the cover plate for the fuel and the combustion chambers, said view also showing the parts carried by said plate; 70

Fig. 7 is an end view of the parts shown at Fig. 6, and

Fig. 8 is a detail perspective view showing 75 the fuel receptacle and means for supporting the same.

In the said drawings 10 designates the combined boiler and radiator as a whole, comprising a series of similarly formed 80 sections presenting the general shape or outline of ordinary radiator sections. Of said sections the middle sections 11^a, 11^b, 11^c, in addition to acting partly as heat emitting surface, serve principally as the boiler or 85 heat absorbing members, while the sections secured to the ends of said sections 11^a and 11^c, serve primarily as heat emitting surface.

Each of the boiler sections 11^a, 11^b, 11^c 90 has its lower front portion recessed at 12 to form a combustion chamber 13 within which is located a burner 14. The upper end of said burner extends through an opening in a horizontal plate 14^a supported upon 95 lugs 14^b, the opening in said plate 14^a being larger in diameter than said burner so as to provide an annular air space 14^c.

The portions of said boiler sections 11^a, 11^b, 11^c, above and to the rear of the combustion 100 chamber 13 are provided with rims or flanges 15, 15 whose edges meet when said sections are assembled, and centrally of said boiler sections 11^a, 11^b, 11^c, their opposing

surfaces are provided with webs or fins 15^a, which meet and form a revertible flue 15^b. Each of said webs or fins 15^a extends downwardly from a point near the top of the 5 sections and thence rearwardly and downwardly and rearwardly again adjacent the rear lower edge of the section. The vertical portions of said webs or fins 15^a, also serve to form the rear wall of the combustion 10 chamber 13, while its side walls are formed by solid partitions 16, 16 formed as a part of the boiler sections 11^a, 11^c.

The boiler sections 11^a, 11^b, 11^c have their 15 rims or flanges 15, 15 partly cut away at the rear of said sections to form an outlet opening 17 over which is secured a plate 18 having a flanged opening 19 therein adapted to be connected to a suitable flue or stack communicating with the outer atmosphere.

20 The radiator sections 11, 11 adjoining the boiler sections 11^a, 11^c, are also recessed similar to said boiler sections 11^a, 11^b, 11^c, to form chambers or compartments 20, 20 and are provided along their recessed edges with 25 rims or flanges 21, 21 which serve to form the top, bottom and rear walls for said chambers or compartments 20, 20. In order to insure a circulation of air through said chambers or compartments 20, 20, the upper 30 and lower horizontal portions of the rims or flanges 21, 21, may be provided with recesses or apertures 22, 22.

The side walls of the chambers or compartments 20, 20 are formed by solid partitions 23, 23 formed integrally with the 35 end sections 11^a, 11^c.

The end sections 11^a, 11^c are also provided with feet 24, 24, in order to support the entire apparatus at a suitable height above the 40 floor.

It will, of course, be understood that the portions of the boiler and radiator sections which are not occupied by the chambers or compartments 13, and 20, 20, are hollow and 45 form water flues, and that all of said sections are provided upon both sides, adjacent to their upper and lower edges with bosses 25 into which are fitted connecting nipples 26.

27 denotes a front or cover plate which is 50 secured at its edges to the sections 11^a, 11^c, 11^b, and is provided with openings 28, 28 registering with the chambers or compartments 20, 20, and a smaller opening 29 registering with the intermediate or combustion 55 chamber or compartment 13.

The openings 28, 28 are provided with doors 30, 30 which are pivotally secured at their lower edges to the front or cover plate 27, and provided with centrally located 60 vertical sight apertures 30^a, 30^a, and the opening 29 is provided with a similarly operating door 31 having a sight opening 31^a therein provided with a transparent section of suitable material.

65 Upon the inner side of the front or cover

plate 27 adjacent to its lower edges is secured a longitudinal pipe 32 having rearwardly extending horizontal branches 33, 33 to whose inner ends are secured pans 34, 34 located in the chambers or compartments 20, 70 20, and an intermediate branch 35 to the inner end of which is secured the burner 14.

Upon the inner side of each of the doors 30 is secured a glass container or font 36 for the hydrocarbon or liquid fuel with 75 which the burner 14 is to be operated. Each of said containers or fonts 36, is provided at its base with a normally closed, spring-pressed valve 37, having a projecting stem 38, and each of said containers or fonts 36 80 is so positioned upon its door 30 with respect to its coöperating pan 34 in its respective chamber or compartment 20, that when said door 30 is fully closed, the projecting stem 38 of the valve 37 on said container or font 85 36 will engage the bottom of said pan 34, and open said valve 37, and permit a certain amount of fuel to enter and partly fill the said pan 34.

In order to permit of the easy removal 90 of the containers or oil fonts 36 from their respective doors, and to hold the same duly in position thereon when said doors are opened or closed, said doors are provided upon their rear sides with segmental, skeleton frames 39, 39, comprising a pair of flanged side members 40, 40, secured together by transverse members 41, 41^a, 42. The member 42 is provided at its middle with an upwardly extending tongue or projection 43 which is adapted to engage with a projecting edge of a strap or frame member 44 embracing the lower edge of the container or font 36. The said projection 43, and the transverse member 41^a serve to 100 hold the container or font duly in position upon the door 30 while the latter is being opened or closed.

In order to permit of the filling of the apparatus with fluid or water, a filling nozzle 45 is secured to one of the end sections 11^a, and provided with a plug 46 for sealing the same. The said nozzle 45 is located at such height as to prevent the over-filling of the apparatus, and to provide sufficient 110 space to permit of the expansion of the water or fluid.

The operation of the apparatus is mainly 115 obvious. It is to be noted, however, that in operation the hot gases and products of combustion from the combustion chamber 13 in passing upwardly and downwardly through the flues to the outlet 18 at the rear of said boiler sections impinge upon the surfaces of said sections, and serve to heat the water 120 therein. As the water within the boiler sections becomes heated it rises to the top thereof and then flows therefrom through the upper connecting nipples into the radiator sections which will be heated thereby. 125 130

As the water within the radiator sections cools, by reason of its giving up its heat to the surroundings, it will flow downwardly through the radiator sections from which 5 it will be returned through the lower connecting nipples to the bottom of the boiler sections where it will again be heated.

In operation the outlet 18, and the stack or uptake serve as a discharge for the products of combustion, as well as any odors which might be produced or caused in the 10 operation of the apparatus.

Further, it will be noted that as the oil receptacles are disposed within the radiator 15 sections the oil will become sufficiently heated to insure a high degree of combustion efficiency.

It is to be noted particularly that all of the operating parts, or parts which may require 20 cleaning or attention are secured to and form a part of the front plate 27 so that whenever it becomes necessary to examine or clean said parts, or any of them, it merely requires the removal of the securing means 25 of the front plate whereupon the same, and the operating parts carried thereby, may be removed as a unit.

Having thus described my said invention what I claim and desire to secure by Letters 30 Patent is:—

1. An apparatus of the character described comprising a plurality of connected sections, certain of said sections constituting a boiler and other of said sections constituting a 35 radiator, said boiler having a chamber formed therein, said radiator having a compartment formed therein, heat producing means positioned within said chamber, and a source of fuel supply positioned within 40 said compartment and communicating with said heat producing means, substantially as specified.

2. An apparatus of the character described comprising a plurality of connected sections, 45 certain of said sections constituting a boiler and other of said sections constituting a radiator, the sections constituting said boiler having recesses formed therein and registering with one another to form a chamber, 50 the sections constituting said radiator having recesses formed therein and registering with one another to form a compartment, heat producing means positioned within said chamber, and a source of fuel supply positioned within 55 said compartment and communicating with said heat producing means, substantially as specified.

3. An apparatus of the character described comprising a plurality of connected sections, 60 certain of said sections constituting a boiler and having a chamber formed therein, a flue communicating with said chamber and positioned between adjacent sections of said boiler, said flue extending upwardly from 65 said chamber and then extending down-

wardly in rear of said chamber and having an outlet adjacent the lower end of said boiler, and heat producing means positioned within said chamber, substantially as specified.

70

4. An apparatus of the character described comprising a plurality of connected sections constituting a combined boiler and radiator, heat producing means and a source of fuel supply therefor positioned within said connected sections, and means secured to said sections and carrying said heat producing means and said source of fuel supply, substantially as specified.

75

5. An apparatus of the character described comprising a plurality of connected sections constituting a combined boiler and radiator, a heat-producing element and a source of fuel supply therefor disposed within said connected sections, and a plate secured to 85 said sections and carrying said heat-producing element and said source of fuel supply, substantially as specified.

80

6. An apparatus of the character described comprising a plurality of connected sections constituting a combined boiler and radiator, a heat-producing element and a source of fuel supply therefor disposed within said connected sections, and a plate removably secured to said sections and carrying said 95 heat-producing element and said source of fuel supply, substantially as specified.

90

7. An apparatus of the character described comprising a plurality of connected sections constituting a combined boiler and radiator, 100 receptacles in said boiler and radiator, a closure for said receptacles, a heat-producing element and a source of fuel supply carried by said closure and extending into said receptacles, substantially as specified.

105

8. An apparatus of the character described comprising a plurality of connected sections constituting a combined boiler and radiator, a receptacle in said boiler and a receptacle in said radiator separated from the receptacle in said boiler, a plate secured to said boiler and radiator and closing said receptacles, a burner and a source of fluid fuel supply secured to said plate and extending into said receptacles, substantially as 115 specified.

110

9. An apparatus of the character described comprising a plurality of connected sections, certain of said sections constituting a boiler and other of said sections constituting a 120 radiator, the sections constituting said boiler having recesses formed therein and registering with one another to form a chamber, the sections constituting said radiator having recesses formed therein and registering with one another to form a compartment, a closure for said chamber and said compartment, a heat producing element carried by said closure and extending into said chamber, and a source of fuel supply carried by 125

120

125

130

said closure and extending within said compartment, said source of fuel supply communicating with said heat producing element, substantially as specified.

- 5 10. An apparatus of the character described comprising a plurality of connected sections constituting a combined boiler and radiator, a receptacle in said boiler, a receptacle in said radiator, a plate secured to 10 said sections and covering said receptacles, said plate being provided with an opening registering with said radiator receptacle, a hinged door carried by said plate for closing said opening, a burner carried by said 15 plate and disposed within said boiler receptacle, and a source of fuel supply carried by said door and communicating with said burner, substantially as specified.

11. An apparatus of the character described comprising a plurality of connected 20 sections constituting a combined boiler and radiator, a receptacle in said boiler, a receptacle in said radiator, a plate secured to said sections and covering said receptacles, 25 said plate being provided with an opening registering with said radiator receptacle, a hinged door carried by said plate for closing said opening, a burner carried by said plate and disposed within said boiler receptacle, and a source of fuel supply removably 30 carried by said door and communicating with said burner, substantially as specified.

12. An apparatus of the character described comprising a plurality of connected 35 sections constituting a combined boiler and radiator, a receptacle in said boiler and a receptacle in said radiator, a plate secured to said sections and covering said receptacles, a pipe secured to said plate, a burner, 40 and a pan connected to said pipe and extending respectively into the receptacles in

said boiler and radiator, an opening in said plate, a hinged cover on said plate and registering with said opening, a fluid fuel receptacle secured to said hinged cover and 45 movable therewith, and an outlet on said fuel receptacle adapted to extend into said pan, substantially as specified.

13. An apparatus of the character described comprising a plurality of connected 50 sections constituting a combined boiler and radiator; the intermediate sections being recessed to form a plurality of separated chambers of which one is formed in said boiler and the others in said radiator, a 55 flue in said boiler extending from the receptacle therein, a plate secured to said section and covering said receptacles, hinged covers on said plate providing access to said receptacles, a pipe secured to said plate, 60 branches extending rearwardly therefrom, a burner connected to one of said branches, pans connected to the other of said branches, said burner and pans extending respectively 65 into the receptacles in said boiler and radiator, oil receptacles carried by the hinged covers of said radiator receptacles, outlets on said oil receptacles adapted to extend into said pans, and normally closed valves for 70 said outlets adapted to be opened when the outlets of said oil receptacles are adjusted to operative position within their respective 75 pans, substantially as specified.

Signed at the city of New York, in the county and State of New York, this 11th day of November, one thousand nine hundred and sixteen.

ANDRÉ M. MERTZANOFF.
